ADJUSTABLE BOBBIN AND BATTERY HOLDER

William B. Cathey, Anderson, S. C.

Application April 9, 1948, Serial No. 19,984

5 Claims. (Cl. 139—251)

1

The present invention relates to new and useful improvements in adjustable bobbin and battery holders for looms of a type disclosed in my co-pending application Serial No. 744,362, filed April 28, 1947 and more particularly to means for effectively holding bobbins in different types of batteries wherein the height of the bobbin with respect to the holder is not always uniform.

In some types of batteries the bobbins are positioned higher than in others and accordingly it is an object of the present invention to provide a bobbin-holding plunger attached in position to a battery and constructed to effectively hold bobbins therein where a substantially wide variation occurs in the height at which the bobbin is supported.

A further object is to provide an adjustable bobbin and battery holder adapted for attachment to the usual bobbin battery of a loom for preventing movement of the bobbin and battery and particularly to prevent the bobbin from turning in the battery, thereby reducing filling breakage on the change and which necessitates stoppage of the loom as well as resulting in an imperfect weave and loss in production.

Another object is to provide means for holding the loom battery against reverse or backward movement during operation of the loom and also to hold the disk and other parts of the battery against vibration to thus reduce wear of the moving parts.

A further object is to provide a device of this character of simple and practical construction, which may be mounted in position on the loom without necessitating any material changes or alterations in the construction thereof, and which, at the same time, is efficient and reliable in operation, relatively inexpensive to manufacture and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a transverse sectional view of a loom battery showing the bobbin holding attachment in position thereon;

Figure 2 is a perspective view of the detent pawl for the battery;

Figure 3 is a group perspective view of the front and rear plungers of the bobbin holder;

Figure 4 is a perspective view of the bracket for the rear plunger;

Figures 5, 6 and 7 are enlarged fragmentary side elevational views of modified head constructions for the rear plunger; and

Figure 8 is a fragmentary side elevational view showing the modification of Figure 6 in position in the bracket.

Referring now to the drawings in detail wherein for the purpose of illustration I have dis-

2

closed a preferred embodiment of the invention, the numeral 5 designates a loom battery disk of conventional construction and on which the bobbins 6 are supported. The usual transfer hammer is shown at 7 which is pivoted, as at 8, and includes a downwardly extending arm 9 operatively connected to the dog 9a.

The loom also includes the battery stand 1, lay 2, and a shuttle box 3 for receiving a shuttle 4 from the running shuttle of the loom, and to the stand is secured an angle bracket 11 including an upwardly projecting forwardly curved fixed guide or abutment 12 for the bobbins 6, the guide or abutment 12 having a square shaped opening 13 therein formed with a beveled countersunk lower edge 14.

A sectional plunger composed of rear and front longitudinally aligned sections 15 and 16 is slidably mounted on the bracket 11, the rear section 15 being square shaped in cross section 20 at its rear end, and curved downwardly as shown at 15a and slideable in the opening 13. The curved rear end of plunger section 15 is formed with a vertical groove 17 aligning with the similar groove 18 formed in the outer surface of the upstanding abutment 12 of the bracket 11. The front end of the rear section 15 of the plunger is threaded as at 15b.

The front plunger section 16 is slidably mounted in a guide 20 secured to the other end of the bracket 11, the front section 16 having a collar 21 secured in longitudinally adjusted position thereon by a set screw 22.

A pair of nuts 23 and 24 are threaded on the end 15b of the rear plunger 15, and mounted thereon between the nut 23 and the upstanding abutment 12 of the bracket 11 is a relatively light coil spring 25. A rear relatively heavy coil spring 26 surrounds the adjacent ends of the plunger sections 15 and 16 with one end of the spring 26 bearing against the collar 21 and the other end of the spring bearing against the nut 24, the spring 26 holding the adjacent ends of the plunger sections in longitudinal alignment and in spaced apart relation with respect to each other.

The front plunger 16 is positioned for engaging the arm 9 of the transfer hammer 7 and with the curved rear end 15a of the rear plunger 15 in position for engaging the bobbins 6. The inner ends of the bobbins are usually provided with annular ribs (not shown) adapted to seat in the grooves 17 and 18, and the coil spring 26 exerts its influence on the plunger 15 to project the same rearwardly of the upturned abutment 12 of the bracket to firmly hold the bobbin, as shown in Figure 1 of the drawings.

Retrograde movement of the hopper is prevented by the usual detent pawl 27 provided with a lateral lug 29 carried by an extension 32 for engaging the inner periphery of the flange 30 of the ratchet wheel 31. The usual dog 33 is pivoted to hammer 7 and is provided with a lug 35 for engaging the teeth of ratchet 31 and coacts with

detent pawl 27 during the operation of the transfer mechanism.

In the operation of the device, when hammer 7 starts its downward motion, its downwardly extending arm 9 releases pressure against plunger section 16, allowing spring 25 to withdraw curved end 15a from bobbin 6 and to position end 15a in opening 13 substantially flush with guide or abutment 12 and with the grooves 17 and 18 aligned to receive the usual ring on the bobbin but (not shown) to guide the bobbin during its transfer.

When hammer 7 starts its upward movement to return to its original position, arm 9 of the hammer comes into contact with plunger 16, moving it forward. Ratchet latch 33 carried by hammer 7 rotates disk 5 moving the next bobbin into position for engagement by the plunger. The speed or weight with which arm 9 of the hammer comes into contact with plunger 16 simultaneously compresses spring 26 allowing latch 27 to drop in place to engage gear 31, and the recoil of spring 26 moves plunger 15 forwardly against the bobbin to prevent the bobbin from turning. Also the pressure of plunger 15 against the bobbin in turn causes gear 31 to press tightly against detent pawl 27. This steadies and braces the disk 5 and prevents excessive wear of the moving parts due to loom vibration.

The detent pawl 27 also prevents reverse or backward rotation of the gear 31 and disk 5 when plunger 15 moves rearwardly and thus holds the bobbin in proper position in line with the hammer for inserting the bobbin into the shuttle.

The downwardly curved rear end 15a of rear plunger 15, in its rearwardly projected position will ride under the bobbin below its center to force the bobbin upwardly to more effectively hold the bobbin in the battery.

The curvature of the plunger also enables the same to effectively hold the bobbins which may not be carried at uniform height in batteries of different types and without necessitating a change in the holder.

To further compensate for variations in the height of the bobbins the head 15a of the rear plunger 15 is especially designed and formed with a downward extension 15c, as shown in Figure 5, for use with low bobbins or with an upward extension 15d, as shown in Figure 6, for use with higher bobbins. A plain head 15e, as shown in Figure 7, is provided for use with bobbins held in an in-between or normal position.

The face of each head is also formed with a horizontal groove 17a intersecting vertical groove 17 to afford greater traction against the bobbin between the usual bobbin rings.

In view of the foregoing description taken in conjunction with the accompanying drawings it is believed that a clear understanding of the construction, operation and advantages of the device will be quite apparent to those skilled in this art. A more detailed description is accordingly deemed unnecessary.

It is to be understood, however, that even though there is herein shown and described a preferred embodiment of the invention the same is susceptible to certain changes fully comprehended by the spirit of the invention as herein described and the scope of the appended claims.

Having described the invention, what is claimed as new is:

1. A bobbin holding device for loom batteries comprising a bracket mounted on a loom and

having an opening and a plunger slidable in the opening and having a downwardly curved extension at its rear end engaging a bobbin carried by a battery at a point below the center of the bobbin to partially extend under the rounded lower side of the bobbin in a position to exert an upward pressure on the bobbin and a rearward pressure on the battery.

2. A bobbin holding device for loom batteries comprising a bracket mounted on a loom and having a non-circular countersunk opening, a non-circular plunger slidable in the opening and having a downwardly curved extension at its rear end engageable with a bobbin carried by a battery at a point below the center of the bobbin to partially extend under the rounded lower side of the bobbin in a position to exert an upward pressure on the bobbin and a rearward pressure on the battery, means projecting the plunger into bobbin engaging position, and spring means retracting the plunger, said curved end of the plunger seating in the countersink of the opening when retracted.

3. A bobbin holding device for loom batteries comprising a bracket carried by a battery stand and having an upwardly projecting forwardly curved rear end provided with a non-circular opening, and a spring projected plunger conformably received in the opening, the rear end of the plunger engaging a bobbin as it approaches its position for delivery from the battery to the shuttle, said bobbin engaging end of the plunger having a vertical bobbin ring engaging groove and a horizontal groove intersecting the vertical groove, said horizontal groove forming an anti-slipping serrated face on the plunger for gripping the bobbin.

4. A bobbin holding device for loom batteries comprising a bracket carried by a battery stand and having an upwardly projecting forwardly curved rear end provided with a non-circular opening, a spring projected plunger conformably received in the opening for sliding movement into and out of engagement with a bobbin as it approaches its position for delivery from the battery to the shuttle, and a downwardly projecting extension on the rear end of the plunger engaging a bobbin below its center.

5. A bobbin holding device for loom batteries comprising a bracket carried by a battery stand and having an upwardly projecting forwardly curved rear end provided with a non-circular opening, a spring projected plunger conformably received in the opening for sliding movement into and out of engagement with a bobbin as it approaches its position for delivery from the battery to the shuttle, and an upwardly projecting extension on the rear end of the plunger engaging a bobbin below its center front, said plunger exerting an upward pressure on the bobbin at one side thereof.
